DIPPER TOOTH

George W. Mork, South Milwaukee, Wis., assignor to Bucyrus-Erie Company, South Milwaukee, Wis., a corporation of Delaware

Application May 20, 1936, Serial No. 80,639

2 Claims. (Cl. 37—142)

My invention relates to new and useful improvements in teeth for excavators, and more particularly for excavators of the dipper type, although my construction could equally well be used on skimmer scoops and drag buckets.

It is old in the art, with respect to such a tooth, to employ a tooth base for attachment to the lip of the dipper, and to secure to such base a renewable reversible wedge-shaped point, the securing being done in various ways.

It is even old to have the point provided with a rearwardly projecting tang, which fits into a slot in the base, and is secured therein by means of a wedge driven transversely through the base and the tang. Such wedges have usually been circular in cross section, although sometimes elliptical, but either of these two shapes are found to perform merely the function of securing the point against longitudinal motion, without appreciably securing the tang against wobbling.

Accordingly it is the principal object of my invention to provide such a construction of base point and tang, and each of them, that the wedge will perform the dual function of securing the point to the base against longitudinal motion, and at the same time will secure the tang against lateral wobbling in the slot which receives it. This is very important, in order to prevent wear on the base by the point, which is apt to be made of harder material.

In addition to my principal object, above stated, I have worked out a number of novel and useful details, which will be readily evident as the description progresses.

My invention consists in the novel parts, and in the combinations and arrangements thereof, and in the specific construction of each of the three individual elements of my invention, each being taken as a distinct and separate entity. These novel features are defined in the appended claims, and one embodiment thereof is exemplified in the accompanying drawing, which is hereinafter described and explained.

Throughout the description, the same reference number is applied to the same member or to similar members.

Figure 1 is a side elevation, partly in section, of my tooth base, taken along the lines 1—1 of Figure 2.

Figure 2 is a plan view of this same base taken along the lines 2—2 of Figure 1.

Figure 3 is a plan view, corresponding to the viewpoint of Figure 2, of my copending tooth point.

Figure 4 is a side elevation of my said point. Figure 5 is an end view of the large end of my wedge taken along the lines 5—5 of Figure 6.

Figure 6 is a side view of this wedge. 5

Figure 7 is an end view of the small end of this wedge taken along the lines 7—7 of Figure 6.

Figure 8 is a plan view assembly of the elements shown separately in Figures 2, 3 and 6. 10

Referring to the drawing, it will be seen that the tooth base of Figures 1 and 2 is bifurcated into two rearwardly projecting portions 11 and 12, to embrace the edge of the dipper lip 10. The lip extends into space 13 and may be secured 15 to the tooth base by rivets (not shown) inserted through holes 14. The method of attaching the base to the dipper lip forms no part of my invention.

If desired, the base may be provided with 20 stiffening ribs 15.

The base is provided with two forwardly projecting supporting portions 16, between which lies a slot 17, partly open and partly extending into the body of the base. 25

Turning now to Figures 3 and 4 we see that my tooth point 18 is wedge shaped, and has two sockets, or supported portions, 19, adapted to engage the supporting portions 16 of the base.

Between these two sockets lies a rearwardly 30 projecting tang 20.

Now comparing the construction of the base shown in Figures 1 and 2 with that of the point shown in Figures 3 and 4, it will be seen that the base has a hole 21, and that the point has 35 a somewhat corresponding hole 22. The outstanding feature of these holes is as follows. The hole 21 in the base has two inclined faces 23 on its forward side, these two faces being disposed at substantially right angles to each other. 40 The hole 22 of the tang of the point has two inclined faces 24 on its rearward side, these two faces being disposed at substantially right angles to each other.

These faces 23 and 24 are so disposed with relation to each other that when my wedge, which will now be described, is driven through holes 45 21 and 22, faces 25 of the wedge engage faces 23 of the hole in the base, and faces 26 of the wedge engage faces 24 of the hole in the tang 50 of the point, thus not only clamping supported portions 19 of the point securely against supporting portions 16 of the base, but also clamping the tang 20 of the point against lateral wobbling in the slot 17 of the base. 55

When my wedge has been firmly driven into holes 21 and 22, as above described, its bendable small end 27 is hammered over to fit into socket 28 on the base, thus securing the wedge in position.

When, in the claims, I use the word "transversely" in referring to the direction in which the slots are cut through base and tang for the insertion of the wedge, I mean substantially parallel to the digging edge of the tooth, as contrasted with being substantially perpendicular to that edge.

Having now described and illustrated one form of my invention, I wish it to be understood that my invention is not to be limited to the specific form or arrangement of parts hereinbefore described, except in so far as such limitations are specified in the appended claims.

I claim:

1. In a tooth for excavators, the combination of: a tip, having a digging edge, a supported portion, and a rearwardly projecting tang; a base, having a supporting portion, to engage the supported portion of the tip, and a slot for the tang of the tip; and a wedge; there being aligned

longitudinally disposed slots transversely cut through the base and the tang, each such slot through the base having at its forward end a pair of flat forward bearing faces rearwardly inclined at substantially the same angle to the direction of application of the tang, and each such slot through the tang having at its rearward end a pair of flat rearward bearing faces forwardly inclined at substantially the same angle to the direction of application of the tang; the wedge having two pairs of faces, to engage these respective pairs of bearing faces.

2. In a tip for an excavator tooth, the combination of: a digging edge; a supported portion, adapted to engage the supporting portion of a tooth base; and a rearwardly projecting tang, adapted to engage a slot on the tooth base, and having itself a transversely cut longitudinally disposed slot, which slot has at its rearward end a pair of flat rearward bearing faces forwardly inclined at substantially the same angle to the direction of application of the tang and adapted to engage corresponding faces on a locking wedge.

GEORGE W. MORK. 25
